UNITED STATES PATENT OFFICE.

EBENEZER A. W. JEFFERIES, OF PHILADELPHIA, PENNSYLVANIA, ASSIGNOR
TO WALTER WOOD, OF SAME PLACE.

ADJUSTABLE HYDRAULIC CYLINDER FOR FLANGING-PRESSES.

SPECIFICATION forming part of Letters Patent No. 550,916, dated December 3, 1895.

Application filed September 20, 1895. Serial No. 563,061. (No model.)

To all whom it may concern:

Be it known that I, EBENEZER A. W. JEFFERIES, a citizen of the United States, residing at the city of Philadelphia, in the county 5 of Philadelphia and State of Pennsylvania, have invented certain new and useful Improvements in Adjustable Hydraulic Cylinders for Flanging-Presses, of which the following is a specification.

10 My invention has relation to a hydraulic flanging-press of the type in which the flanging-die is carried by the ram or piston of a hydraulic cylinder; and it relates to the construction and arrangement of such hydraulic 15 cylinder, whereby the same may be adjusted in the head-plate carrying or guiding the cylinder for the purpose of flanging fire-box mouths of locomotive-boiler fronts and other similar articles.

20 The principal objects of my invention are, first, to provide in a hydraulic flanging-press a die adapted to flange fire-box mouths for locomotive-boiler fronts and other similar articles in which the position of the interior 25 opening is variable; and, second, to provide in a hydraulic flanging-press a die carried by the piston of a cylinder adjustable laterally or longitudinally or in both directions in the head-piece of the press.

30 My invention, stated in general terms, consists of a hydraulic cylinder operating a flanging-die adjustable in the head-piece of the press; and my invention further consists of an adjustable die-carrying cylinder for hydraulic 35 flanging-presses constructed and arranged in substantially the manner herein-after described and claimed.

The nature and scope of my invention will be more fully understood from the following 40 description, taken in connection with the accompanying drawings, forming part hereof, and in which—

Figure 1 is a top or plan view of the head-piece and supporting-standards of a hydraulic 45 flanging-press embodying features of my invention and illustrating in connection with said head-piece the laterally-adjustable die-carrying hydraulic cylinder in said head-piece. Fig. 2 is a front elevation of the upper 50 part of a hydraulic press embodying features of my invention and illustrating the

head-piece and adjustable die-carrying hydraulic cylinder. Fig. 3 is a side elevation of Fig. 2. Fig. 4 is a top or plan view of the head-piece, showing the die-carrying hydraulic cylinder adjustable longitudinally therein; and Figs. 5 and 6 are respectively front and side views of an unflanged and flanged blank for a fire-box mouth of a locomotive-boiler front.

60 Referring to the drawings, *a* represents the head-piece or table of a hydraulic flanging-press screwed or otherwise secured to the upper portion of the columns or supporting-standards *b*. At approximately the center 65 of the head-piece or table *a* and extending through the same is formed a slot *d*, which, as shown in Fig. 1, extends laterally across the head-piece or table *a*, or a slot *e* may be formed in said table *a*, extending longitudinally therein, as illustrated in Fig. 4. These 70 slots each cross the middle or center of the table *a* and are slightly larger in width than the external diameter of the hydraulic cylinder *f*, whose piston or ram carries the flanging-die. (Not shown.) Within the slot *d* or *e* may be located the cylinder *f* and secured in any desired position therein.

75 The means which may be employed is as follows: The head-piece *a* is provided on either side of the slot *d* or *e* with the channels or grooves *d'* or *e'*, adapted to receive the head and stem of the bolts *d²* or *e²*, which bolts pass through a clamp-plate *d³* or *e³*, fitted over the upper head of the cylinder *f*. The bolts are secured to the plate *d³* or *e³* and the head of the cylinder secured to the table *a* by screwing down upon the plate the nuts *d⁴* or *e⁴* of the bolts, thus clamping the plate and cylinder to the table. When the cylinder is to be shifted, 90 the nuts of the bolts are loosened, and the heads and stems of the bolts are thereby permitted to move in the slots or grooves *d'* or *e'* of the table.

95 In flanging the blank *h*, and particularly the internal opening *i*, of a fire-box mouth for a boiler front or similar blanks it is necessary that the die carried by the piston of the hydraulic cylinder be adjusted so as to register with said opening *i*, because this opening in 100 blanks of this character varies in its position even in boiler fronts of the same size and

shape. To permit of the adjustment of such die, is provided the adjustment laterally or longitudinally of the hydraulic cylinder *f* in the piece or table *a*, and thus to bring the die 5 carried by the piston of the hydraulic cylinder into any desired position to register with the openings *i* of the blank. The successive positions of the cylinder *f* are indicated in full and dotted lines in Fig. 1 of the drawings.

Having thus described the nature and objects of my invention, what I claim as new, and desire to secure by Letters Patent, is—

1. In a hydraulic flanging-press, a head piece or table, a hydraulic cylinder and piston 15 or ram carrying a flanging die, and means for adjusting said cylinder in said head piece or table to vary the position of said die, substantially as and for the purposes described.

2. In a hydraulic flanging-press, a head- 20 piece or table having longitudinal or lateral openings and a hydraulic cylinder adapted to be adjustably secured in the openings of said

head piece or table, substantially as and for the purposes described.

3. In a hydraulic flanging-press, a head-piece or table, a hydraulic cylinder or ram, a flanging die operated by said cylinder, the head piece being slotted laterally or longitudinally to permit of the shifting of the cylinder and provided with a groove on either side of 30 the lateral or longitudinal slots and parallel therewith, a bolt adapted to be shifted in said grooves, and a plate adapted to be clamped to said head-piece by said bolt to secure the cylinder, substantially as and for the purposes described.

In testimony whereof I have hereunto set my signature in the presence of two subscribing witnesses.

EBENEZER A. W. JEFFERIES.
